UNITED STATES PATENT OFFICE.

EDMUND PAUL EHRLINGER, OF JANEVILLE, WISCONSIN.

PRINTER'S GALLEY.

Application filed July 26, 1924. Serial No. 728,455.

To all whom it may concern:

Be it known that I, EDMUND P. EHRLINGER, a citizen of the United States, and resident of Janesville, in the county of Rock 5 and State of Wisconsin, have invented certain new and useful Improvements in Printers' Galleys; and I do hereby declare that the following is a full, clear, and exact description thereof.

10 This invention relates to printers' galleys.

Heretofore, in placing advertising matter or other insertions in forms which have been practically made up, it has been the 15 custom to loosen the side and foot sticks of the chase pending the arrival of the insertion. When the insertion is received, it is usually picked up, a line at a time, and placed in the space left for it in the chase.

20 In printing, time is at a premium and these operations requiring as they do a material length of time and considerable skill on the part of the make up man, are frequently the cause of delay and error in arrangement of the parts of the insertion and adjacent parts of the previously set up type.

25 This invention is designed to overcome the above noted defects, and objects of such invention are to provide a printer's galley which insures the easier, quicker, and more certain placing of the insertion within the chase after the page of type has been practically made up, which is adapted to have the insertion slid from either end thereof, and which is preferably formed of a width corresponding to the actual width of column space left in the partially set up chase.

30 An embodiment of the invention is shown 40 in the accompanying drawings, in which:—

Figure 1 is a plan view of the galley.

Figure 2 is a longitudinal sectional view on the line 2—2 of Figure 1.

45 Figure 3 is a transverse sectional view on the line 3—3 of Figure 1.

The galley comprises a main or body portion having a bottom 1 and sides 2. This body portion is open at its ends and is in effect an elongated channel.

50 An end 3 of any suitable material is provided and is adapted to fit between the sides 2. This end is riveted or otherwise secured to inturned arms 4 of supporting side straps 5. These side straps form in effect links and

are pivoted by means of the rivets or similar members 6 to the central portion of the sides 2 of the body member. Preferably the extreme ends of the sides 2 of the main member are slightly rounded, as may be seen from Figure 2, so as to facilitate the rocking of the end 3, into either position at either of the ends of the galley. It is to be noted further that the end 3 rests upon the bottom or overlaps the bottom of the main member and thus prevents such end from being swung downwardly past the main member.

55 It is to be noted that the inner heads of each of the several rivets are countersunk and set flush with the inner surface of the 60 galley.

65 It is intended that these galleys shall be made of the exact column width desired, for instance, one, two, three or any number of 70 column widths.

75 In using this device, the insertion is prepared in the galley in the usual manner and is sent to the printer. The printer, as is usually the custom, has the chase or page practically set up with a space left for the 80 insertion. The make-up man merely rocks the end to the desired position to permit the sliding of the insertion from the galley into the chase. The freedom of choice as to direction of sliding permits a very great 85 flexibility in the assembling of the insertion within the partially set up type, and does not require the picking of the insertion line by line from the galley, and the placing of 90 such lines separately into the chase.

95 Further, it will be noted that due to the fact that the galley is made of the actual width of the space left for it, it may be placed in position and the insertion slid 100 from it. It is further to be noted that the reversibility of the end of the galley provides increased flexibility in the actual assembling of the ad or insertion for the reason that the insertion may be started at one end of the galley and if it is desired to work from the other end, this may be easily accommodated by reversing the end of the galley and partially sliding the set type inwardly. Thereafter, the other end of the insertion may be partially formed, 105 if desired, and the two parts slid together into position. This may not be called under ordinary type setting conditions but may

be found highly desirable in easily positioning cuts, blocks and other inserts made within the insertion itself.

Further it is to be noted that the device is extremely simple and may be cheaply produced and is free from complicated construction, projecting ears, adjusting screws, and other detrimental features.

Although the invention has been described in considerable detail, it is to be understood that the invention may be variously embodied and is, therefore, to be limited only as claimed.

I claim:

- 15 1. A printer's galley comprising a body having a bottom and upturned sides, an end

member, and means secured to said end member and pivotally joined to the central position of said body.

2. A printer's galley comprising a body having a bottom and upturned sides, a pair of levers pivotally joined to the central portion of said sides, and an end member carried by the outer end of said levers and adapted to fit within the body and rest upon the bottom thereof.

In testimony that I claim the foregoing I have hereunto set my hand at Janesville, in the county of Rock and State of Wisconsin.

EDMUND PAUL EHRLINGER.
